LAPEL MICROPHONE

Richard W. Carlisle, Haddonfield, N. J., assignor
to Radio Corporation of America, a corpora-
tion of Delaware

Application April 30, 1934, Serial No. 723,230

2 Claims. (Cl. 179—121)

The present invention relates to microphones, and more particularly to the variety thereof adapted to be worn on the person of a performer in order to pick up his voice.

5 Microphones of the aforesaid general type have been previously made, but they have had undesirable characteristics both as to inherent noise and as to frequency response, and particularly as to frequency response from the voice of the performer.

10 I therefore propose to provide a microphone of the "ribbon" or "velocity" type which is peculiarly adapted to be worn upon the coat lapel of, or in an equivalent position upon the body of, the performer, and which provides uniform characteristics both as to frequency and as to volume, irrespective of the relative position of the performer's head.

One object of my invention is to provide such a 20 microphone which will provide a uniform volume irrespective of the position of the performer's head in relation to it.

Another object of my invention is to provide such a microphone which will provide a normal 25 frequency response irrespective of the usual directional frequency characteristics of a performer's voice.

Another object of my invention is to provide an 30 improved microphone of the magneto-generative ribbon, or "velocity" type, as distinguished from the pressure-operated resistive or capacitative types of microphones.

Other and ancillary objects of my invention will hereinafter appear to those skilled in the art 35 from a study of the accompanying drawings and a reading of the following specification.

In the drawings:

Fig. 1 is a view of my improved microphone in 40 completely assembled form.

Fig. 2 is a dis-assembled view of the microphone.

Fig. 3 is a diagrammatic illustration of the 45 mounting of my microphone on the coat lapel of a performer.

Fig. 4a is a diagrammatic illustration of the 50 frequency response characteristics of my microphone in one direction.

Fig. 4b is a diagrammatic illustration of the 55 frequency response characteristics of my microphone in a second direction.

Fig. 4c is a diagrammatic illustration of the 60 frequency response characteristics of my microphone in a third direction.

Fig. 5a is a diagrammatic illustration of the 65 volume response characteristics of my microphone in the most remote position of the performer's mouth.

Fig. 5b is a diagrammatic illustration of the 70 volume response characteristics of my microphone in the average position of the performer's mouth.

Fig. 5c is a diagrammatic illustration of the volume response characteristics of my microphone in the nearest position of the performer's mouth.

Referring now to the drawings:

In Fig. 1, 10 represents generally my microphone in assembled form, 11 is the transformer therefore, and 12 is the connecting cord which permits the transformer 11 to repose in a convenient pocket of the performer when the microphone 10 is retained upon his coat lapel by the phosphor-bronze clip 13.

As shown in Fig. 2, the elements of my microphone proper comprise an electro-magnetic unit generally indicated at 14, and hereinafter described in greater detail, a rectangular casing 15 carrying the clip 13, and a plurality of end-plates 16 and 17 which, held toward each other by the screw 18, secure the assembly together.

The screw 18 passes through the hole 19 in one end-plate and is received in the nut 20 secured to the other end-plate. It is, of course, immaterial which end-plate carries the hole and which the nut so long as the head of the screw 18 substantially counterbalances the nut 20.

Between the ends of the unit 14 and each of the end-plates is interposed a felt washer 21 (only one of which is shown) permitting a firm clamping of the unit 14 by the end-plates with sufficient rigidity and yet with sufficiently damped elasticity to permit the unit 14 to be retained firmly and yet non-resonantly in positive but unrigid spaced relationship with the casing 15, 16 and 17. Such construction prevents the transmission of extraneous mechanical noises, such as those due to rubbing of clothes, etc. to the microphone.

To refer now more generally to the construction and purposes of applicant's device:

The principal purpose of using a lapel microphone as contrasted to a stationary microphone in front of a speaker is to permit the speaker to move freely around a studio, stage or lecture platform or turn away from the audience without there being any appreciable change in the intensity or quality of his voice, as heard by the audience, due to the variation in distance and azimuth with respect to the microphone. This reduces the amount of monitoring to a minimum. There is also some advantage to be gained in the fact that it is not necessary in the lapel microphone case to obstruct the audience's view of the speaker.

In ordinary public address, sound re-enforcing, news reel pickup and for many broadcasting purposes, convenience in microphone placement is an important factor. With the lapel microphone it is sufficient merely to hook the microphone into the buttonhole of the speaker's coat lapel in order to permit him to proceed with his speech.

The general requirement of a microphone is 60

uniform response over a specified frequency range. In the case of the ordinary microphone this means that the ratio of the voltage impressed upon the grid of a vacuum tube to the pressure in free space shall be relatively independent of frequency.

It is well known that the quality of the human voice changes as the speaker's head is turned relative to the auditor. In the case of the ordinary microphone, we neglect to compensate for this effect because we really transplant the auditor's hearing mechanism to the position occupied by the microphone and any frequency discrimination merely adds to the naturalness of the action.

In the case of the lapel microphone we are primarily interested in obtaining maximum articulation. The articulation depends essentially upon the shape of the frequency response characteristic, the width and the location in the frequency spectrum of the transmission band.

The diffraction of a plane sound wave around a spherical obstacle was first investigated mathematically by Rayleigh. The theoretical analysis was extended by Stewart who applied it over a limited frequency range to the diffraction of sound around the human head.

For this particular analysis we will assume, following the analysis by Stewart, that a small source (at $\theta=0^\circ$) located on the surface of a sphere 7.5 inches in diameter represents the human voice. The approximate angular position of the lapel microphone is where $\theta=90^\circ$.

The ratio of the pressure at $\theta=0^\circ$ to that where $\theta=90^\circ$ was calculated assuming a plane wave impinging on the bottom of the sphere. Measurements were made of a small source of sound at various distances from a condenser microphone, which indicated that little change in frequency characteristic occurred as the source was moved from a large distance up to the vicinity of the microphone.

Two types of microphones may be used for this particular purpose, namely one whose response corresponds to the pressure in the sound wave, or one whose response is proportional to the particle velocity. Each type has certain inherent advantages and disadvantages for this application.

One of the problems encountered with a lapel microphone is that when a speaker turns his head towards the side away from the microphone, there is a serious loss in intensity of the sound striking the microphone, due to the increased distance between microphone and sound source. The directional characteristics of the bi-directional velocity microphone can be employed to compensate for this change in intensity.

The characteristics of the velocity microphone, consisting of a thin aluminum ribbon freely suspended in a magnetic field, have been described previously in H. F. Olson—Journal of the Soc. of Motion Picture Engrs. vol. 6, page 695 (1931), Journal of the Acoustical Soc. of Amer. vol. 3, page 56 (1931) and Proceedings of the I. R. E., vol. 21, page 655 (1933). These may be summarized by stating that the differential pressure on the ribbon, resulting from the impact of a sound wave, is proportional to the mean distance between the front and rear surfaces, and proportional to frequency. The velocity of the ribbon (and hence the induced voltage) is proportional to this pressure and inversely proportional to the mechanical impedance of the ribbon. The latter

is due to the ribbon mass and the air load, and is proportional to frequency. The ratio of ribbon velocity to free space sound pressure is, therefore, independent of frequency, if there are no obstructions to the path of the sound near the ribbon.

The particle velocity of a spherical wave builds up in the vicinity of the source. A velocity microphone located at a distance r inches from a source will accentuate a low frequency f in the ratio

$$R = \frac{\text{velocity}}{\text{pressure}} = \left(\frac{2100}{rf} \right)^2 + 1$$

It was also shown that the sensitivity is a maximum normal to the ribbon, and decreases off the axis to zero in the plane of the ribbon.

Suppose such a device is placed on the left lapel, as in Fig. 3, with the line normal to the ribbon pointing across the speaker's chest to the point occupied by his mouth when his head is turned away from the microphone. Then as the speaker turns his head towards or away from the microphone, the azimuth of his mouth varies from a region of low sensitivity to that of maximum sensitivity. The directional characteristic is shown in Figs. 5a, b and c, and the ratio of the directional factor to the distance of separation may be seen to be nearly the same for three principal head positions.

This invariance of pickup as the head is turned is a fundamental advantage of the velocity lapel microphone.

Since the directions of minimum pickup are over the speaker's left shoulder or to his lower right side, loudspeakers may be placed there with optimum immunity from feedback.

The ideal frequency characteristic of a pressure-operated lapel microphone would be the inverse of the diffraction characteristic.

The ideal frequency characteristic of a velocity lapel microphone and its associated transformer may be obtained by correcting for the ratio of velocity to pressure. There is a further restriction. As the frequency range is extended, the ideal characteristic would rise steadily towards the higher frequencies. When used in a sound re-enforcing system, this would increase the probability of pickup from the loudspeakers at the frequencies of accentuated sensitivity, with a consequent likelihood of howling. A definite limitation of 12 db. maximum rise with no sharp peaks, using the frequency range of 80 to 7000 cycles, has given very good results.

The microphone consists of a small U-shaped permanent magnet 25 with an extremely thin aluminum ribbon 26 mounted between its poles. This ribbon is one inch long, one thirty-second of an inch wide and one ten-thousandth of an inch thick. A transformer 11 couples the ribbon to a 250 ohm line. The theoretically desirable frequency characteristic was approached in the commercial design by appropriate proportioning of the transformer winding inductances, leakage reactance and distributed capacitance.

The microphone is shown, in assembled and exploded views, in Figs. 1 and 2. The total weight of the microphone is three ounces. It is approximately 1 1/4 inches square and 1 inch thick. A short lead extends from the microphone to the transformer, which may be placed in a side pocket. The microphone parts are enclosed in a perforated metal case lined with silk, with the ribbon on an angle of 45° to the horizontal. A clip on the back of the case is

designed to fit a lapel buttonhole as hereinbefore described.

The lapel microphone may also be used for picking up sound from solo musical instruments such as the banjo or violin, by placing it in a suitable position on the musician's coat, in close proximity to the instrument. It may also be clamped on the instrument, utilizing the directivity characteristics of the microphone to compensate for the directivity of the instrument.

The foregoing portion of this specification has dealt primarily with matters of volume response, and the relation of frequency response thereto will next be considered, with proper consideration 15 of volume response in relation thereto:

It is quite well known that the quality of the human voice changes as the speaker's head is turned relative to the auditor. In the case of ordinary microphone "pickup", we can neglect 20 this because we really "transplant" the auditor's hearing mechanism to the position occupied by the microphone and any frequency discrimination merely adds to the naturalness of the action.

A lapel microphone must accentuate high frequency as compared to the low frequency response in order to compensate for the diffraction of the voice around the head. There is less high frequency in the vicinity of a lapel than there is low frequency. Since the high-frequency end of the characteristic must be the most sensitive, it should not have sharp peaks at which excessive pickup from the loudspeakers (in public address systems) would occur, causing howling. Smoothness of high-frequency response is an inherent characteristic of the ribbon type of microphone and the difficulties of diaphragm and other mechanical resonances are obviated. The ribbon principle is therefore utilized in this design.

40 There are two ways of making a ribbon microphone: velocity actuated or pressure actuated. A velocity actuated lapel microphone consists of a thin aluminum ribbon free to vibrate with the air current, suspended in a magnetic field. 45 This may be made pressure operated by placing air cavities or a labyrinth (a long damped tube) behind the ribbon. In the velocity model, it is found that practically complete compensation for the way the speaker's head is turned is secured by so tilting the ribbon that its most 50 sensitive pickup region is towards the speaker's mouth only when his head is turned to the side away from the microphone; then when he turned his head towards the microphone he turned it 55 towards the region of less response. With this arrangement the advantage of the pressure microphone over the velocity microphone is so small as to be overbalanced by factors of transformer weight and the additional cost of the labyrinth. 60 It so happens that the velocity ribbon accentuates low frequencies for a source near it as in this case. This permits of a transformer to be used which cuts off low frequencies and is therefore a lighter transformer than can be used with the pressure microphone, and this is so small that it may be placed in the same case as the microphone.

In Figs. 5a, b, and c are demonstrated the application of the directional diagrams of the velocity lapel microphone to maintain constant output as the speaker's mouth is turned from side to side. As mentioned above, the most sensitive pickup region is towards his mouth only 75 when he turns it away from the microphone.

The relative sensitivity in any position is the ratio of the sensitivity shown by the directional pattern to the distance of the mouth from the microphone. It may be seen that the values for left and right vary only 5% from the sensitivity at the central position. It will vary slightly for different persons.

For these reasons we have adopted the velocity microphone. Due to the building up of low frequencies by a velocity microphone when used near a sound source, frequency compensation in addition to that discussed previously must be provided at the low frequencies. A velocity microphone located at a distance r inches from the source will accentuate a low frequency f in the ratio

$$R = \frac{\text{velocity}}{\text{pressure}} = \left(\frac{2100}{rf} \right)^2 + 1$$

Thus we have for a distance $r=9$ inches from the source,

$$R = \left(\frac{230}{f} \right)^2 + 1$$

So when

$$f = 460, R = 1.1$$

$$f = 230, R = 1.4$$

$$f = 115, R = 2.24$$

$$f = 57, R = 4.12$$

The microphone itself is a small U-shaped permanent magnet 25 having mounted between its poles a thin aluminum ribbon 26. Figs. 4a, b and c show the general idea. The primary of the transformer 11 connects to the ribbon and the secondary to a line which feeds the input side (250 ohm input) of a public address or broadcasting amplifier. The ribbon dimensions are considerably smaller than in the case of the standard velocity microphone, the magnet air gap is smaller, and the clearance between ribbon and pole pieces is smaller.

In this microphone a considerably smaller and lighter magnet is used than in the case of the standard velocity microphone. This magnet has a narrower air gap than the standard and clearances between the sides of the ribbon and the pole pieces are smaller than in the standard. These clearances may be made small because in the case of a lapel microphone we do not require as much low-frequency sensitivity as in the case of the standard type and, therefore, a higher natural frequency may be adopted for the ribbon. The tighter the ribbon is stretched, the narrower the clearances may be made. Standard velocity microphones have a very loose ribbon tuned to approximately 15 cycles per second and therefore must have a greater gap than the lapel microphone in which the ribbon is preferably tuned between 50 and 100 cycles. The gap is, in the latter instance, determined by four factors: first, the probable sag of the ribbon; second, the minimum spacing to which it can be set in commercial manufacture; third, the diameter of the largest particles of dirt which are apt to get through the silk screen; and fourth, magnetic saturation.

The magnet conformation shown in the drawings is adopted as giving the minimum leakage for any design which would satisfy the space requirements.

The most desirable magnet length, as at present known, is $2\frac{1}{2}$ inch.

It has been shown that in the standard velocity microphone the difference in pressure between the two sides (which corresponds to the force actuating the ribbon) is proportional to the fre-

quency. Furthermore, the impedance of the vibrating system is proportional to the frequency. Therefore, the ratio of the velocity of the ribbon to the pressure in free space is independent of the frequency.

5 The pressure available for actuating the ribbon in the lapel microphone in which the permanent magnet encloses the back is not a simple function of the frequency and the angle of the 10 incident sound with respect to the normal to the face of the ribbon. The magnet structure enclosing the back constitutes essentially an "open pipe". To determine the magnitude and phase at the points p_1, p_2 etc. (Fig. 4a) on the back of the 15 ribbon, we must analyze the structure as an open pipe. At the resonance frequency of the chamber 20 the pressure at the point X_1 is a maximum and the velocity at X_2 is a maximum. Besides resulting in the largest pressure on the back side 25 when resonance obtains, the difference in pressure between the two sides is largest due to the fact that the difference in phase is the value which results in the largest difference in pressure.

25 The response characteristic will then show a rise in the characteristic, after which the response will decrease rapidly with frequency. This is, of course, a desirable characteristic in view of the necessity of having a rising response characteristic to compensate for the characteristics 30 of the human voice for $\theta=90^\circ$.

A magnet longer than the one referred to above causes the peak to occur at a frequency lower in proportion to the magnet length, thus 35 reducing the range.

In the conventional type of ribbon microphone, the response is zero for sounds originating in the plane of the ribbon. However, due to the magnet structure enclosing the back of the magnet, the response at the higher frequencies is not zero for all azimuths of sound originating in the plane of the ribbon. The magnet structure as pointed out above approximates an "open pipe". The phase shift in this cavity differs from 40 45 the phase shift along the outside of the ribbon when sound originates as shown in Fig. 4b.

Of course, at low frequencies, the phase difference is very small. As the resonance frequency of the cavity is approached, the phase 50 difference increases rapidly and, as a consequence, the difference in pressure increases rapidly. The cavity is excited by resonance because the same pressure and phase of the incident sound exist on the two ends of the cavity.

55 When sound originates, as shown in Fig. 4c, we have practically zero response because the speed of propagation in the cavity and in the open is the same. Therefore, the difference in pressure between the two sides of the ribbon is zero. 60 This explains in a general way the behavior of the microphone in a sound field.

It is necessary to associate a transformer with the microphone. The transformer may either be placed in the case with the microphone element or be connected by a short cord 65 70 to the microphone and placed in a side pocket. A transformer has been made small and light enough to go inside the microphone case.

70 There is a slight acoustic rise at the high end (4000-6000 cycles). Below this, the level is made high over the region 2000-4000 cycles by the transformer rise due to the interaction 75 of the distributed capacitance of the trans-

former with its leakage inductance. Low frequencies are then tapered off, starting at 1000 cycles. The entire frequency characteristic is thereby sloped.

The transformer is designed to give a greater 5 step-up ratio than a usual transformer. This is justified by the fact that the range is limited to 7000 cycles, and also that low frequencies are made to slope off steadily below 1000 cycles. The best step-up ratio was determined by trying 10 different taps on the primary. The best low-frequency characteristic is determined by listening to the microphone output for naturalness and distortion as laminations were removed.

Transformer winding data

15

Primary .036 diam. Cu. enamel 12 turns. Resistance .019 ohms.

20

Secondary .006 diam. Cu. enamel 510 turns. Resistance 23 ohms.

Bring out primary conductor in sleeve for terminals.

25

Open-circuit secondary inductance at 1000 cycles, .18 henry.

Coil length $\frac{7}{16}$ ". Inside size $\frac{1}{16} \times \frac{1}{4}$ ". Outside $\frac{1}{8} \times \frac{5}{8}$ " plus leads.

30

One of the factors determining clearance between ribbon and pole pieces was the maximum size of dust particles that could get in. Experiments with screens of balloon cloth and other fabrics of closer mesh than the silk used in screening the production ribbon speakers have brought out no substitute for this silk which did not impair sensitivity. The clearance between ribbon edges and pole pieces which these considerations have led me to adopt is between .005" and .006" on each side of the ribbon.

35

So far as I have been able to discover, the most desirable width for the ribbon is of the order of .078 inch, and the most desirable length for the ribbon is one inch.

40

The magnet is preferably made of 35% cobalt alloy steel having a Rockwell hardness between 60 and 62 and providing a flux density of 45 1400 g. with an air gap of .088".

45

Experience with the magnetic circuit indicates that if a greater ribbon length is chosen not only does the microphone become more bulky but nothing is to be gained for a given weight of magnet. Unless stricter space requirements are to be placed on the microphone, there is no point in making the ribbon shorter. A ribbon thickness of .0001" is preferred.

50

Having now described my invention, I claim:

55

1. In combination with a microphone having its maximum response in a single direction, means for supporting said microphone upon the person of a speaker in such position that the direction of maximum response is in the direction of maximum distance of the speaker's mouth from the microphone.

60

2. The method of securing a uniform response in a microphone independent of the position of the speaker's head, comprising the step of positioning a microphone having a directional response adjacent to the speaker with its direction of maximum response in the direction of the speaker's mouth when turned away from the microphone, and with a direction of less response in the direction of the speaker's mouth when turned most nearly toward the microphone.

65

RICHARD W. CARLISLE.
